US0D1071875S

(12) **United States Design Patent** (10) **Patent No.:** **US D1,071,875 S**
(45) **Date of Patent:** **** Apr. 22, 2025**

(54) **CONTROL DEVICE**

(71) Applicant: **Lutron Technology Company LLC**,
Coopersburg, PA (US)

(72) Inventors: **Chris Dimberg**, Easton, PA (US);
Jason C. Killo, Emmaus, PA (US);
Matthew Philip McDonald,
Phoenixville, PA (US); **Daniel L. Twaddell**, Allentown, PA (US)

(73) Assignee: **Lutron Technology Company LLC**,
Coopersburg, PA (US)

(**) Term: **15 Years**

(21) Appl. No.: **29/898,356**

(22) Filed: **Jul. 26, 2023**

Related U.S. Application Data

(63) Continuation of application No. 17/993,040, filed on
Nov. 23, 2022, now Pat. No. 11,804,339, which is a

(57) **CLAIM**

The ornamental design for a control device as shown and described.

DESCRIPTION

FIG. 1 is a perspective view of a control device showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines illustrate structure or features which form no part of the claimed design.

1 Claim, 4 Drawing Sheets
